UNITED STATES PATENT OFFICE.

JAMES W. THOMPSON, OF WICHITA, KANSAS.

SHELF-CLAMP.

1,333,515.

Specification of Letters Patent.

Patented Mar. 9, 1920.

Application filed April 5, 1919. Serial No. 287,814.

To all whom it may concern:

Be it known that I, JAMES W. THOMPSON, a citizen of the United States, residing at Wichita, in the county of Sedgwick and 5 State of Kansas, have invented new and useful Improvements in Shelf-Clamps, of which the following is a specification.

This invention relates to exhibiting devices, and has for its object the provision of 10 a clamp adapted to be engaged upon the edge of a shelf or the like and which is provided with means for holding a show card, price ticket, or the like.

An important object is the provision of a 15 device of this character which is formed of two parts which are telescopically engaged whereby the device may be quickly and easily adjusted for ready engagement upon shelves, tables, or the like of different thicknesses, and which will remain in firmly 20 secured position without danger of upsetting the adjustment.

A further object is the provision of a 25 device of this character which will be extremely simple and inexpensive in manufacture, highly efficient and durable in use, neat in appearance, and a general improvement in the art.

With the above and other objects and advantages in view, the invention consists in 30 the details of construction to be hereinafter more fully described and claimed, and illustrated in the accompanying drawing, in which—

35 Figure 1 is a perspective view of my device in position upon the edge of a shelf,

Fig. 2 is a cross sectional view through a shelf showing my device in side elevation;

Fig. 3 is a similar cross sectional view 40 through a shelf of greater thickness and showing my device applied thereto, the device also being shown in section, and

Fig. 4 is a cross sectional view on the line 4-4 of Fig. 1.

45 Referring more particularly to the drawing, the letter A designates a shelf, table edge, or the like, upon which my device is adapted to be positioned.

In carrying out my invention I provide 50 two members 10 and 11, both of which are formed from any suitable material, preferably sheet metal, such as brass, galvanized iron, or the like.

The member 10 is formed from an L- 55 shaped or right angular piece of metal including a portion 12 adapted to bear upon

the top of the shelf A and a portion 13 which has its side edges bent upon themselves in slightly spaced relation to the portion 13 to provide retaining flanges 14. 60

The member 11 is similar in shape to the member 10, that is it is L-shaped or right angular and includes the portion 15 corresponding to the portion 12 of the member 10 and engageable beneath the bottom of the shelf A or the like. This member 11 also includes a portion 16 which is of a size to be received within the guide formed by the inturned flanges 14 on the member 10. At the lower part of the portion 16 the member 11 is provided with tongues 17 which are bent upwardly and toward the portion 16 and which have their terminals directed outwardly away from the portion 16 whereby these tongues will constitute 75 clips within which may be engaged a show card, price ticket, or the like, as shown in Figs. 2 and 3.

In the use of the device, the members 10 and 11 are moved toward or away from each other, as the case may be, so that the portions 12 and 15 will be disposed at the proper distance apart to be engaged upon the shelf A, or it might be preferable that the device be first engaged upon the shelf, 80 after which the operator, by pressing with his thumb and forefinger upon the portions 12 and 15 may move the members 10 and 11 together so that the portions 12 and 15 will engage and firmly grip the shelf. Owing 85 to the fact that the portion 16 of the member 11 is telescopically engaged within the guide formed by the flanges 14 on the member 10, these members may be readily adjusted with the utmost ease. 95

When the device is thus positioned upon a shelf or table edge it will be seen that it will be held firmly thereon so that the price ticket or show card B engaged within the clips 17 will be displayed in an efficient 100 manner.

While I have shown and described the preferred embodiment of my invention, it is of course to be understood that I reserve the right to make such changes in the form, 105 construction, and arrangement of parts as will not depart from the spirit of the invention or the scope of the subjoined claim.

Having thus described my invention, I 110 claim:

A device of the character described comprising a pair of members each formed L-

shaped and each including a flat portion adapted to bear against one flat side of a shelf, one member further including a portion extending at right angles to said first named portion and having its side edges extended inwardly toward each other whereby to provide guide flanges, and the other member including a right angularly extending portion engaging within said flanges

whereby said members will be slidably adjustable to accommodate shelves of different thicknesses, and said second named member having pair of spaced clips formed thereon whereby to support a show card, the flat portion of both members being of the same size and shape and parallel. 10 15

In testimony whereof I affix my signature.
JAMES W. THOMPSON.
